Edward H. Dewes
By Alfred W. Eicker, Atty.

UNITED STATES PATENT OFFICE

EDWARD H. DEWES, OF ST. LOUIS, MISSOURI.

WAGON-SKEIN.

SPECIFICATION forming part of Letters Patent No. 688,723, dated December 10, 1901.

Application filed May 11, 1901. Serial No. 59,828. (No model.)

To all whom it may concern:

Be it known that I, EDWARD H. DEWES, a citizen of the United States, residing at St. Louis, in the State of Missouri, have invented 5 certain new and useful Improvements in Wagon-Skeins, of which the following is a specification, reference being had therein to the accompanying drawings.

This invention relates to improvements in 10 wagon-skeins; and it consists in the novel arrangement, construction, and combination of parts, as will be more fully hereinafter described, and set forth in the claims.

The object of this invention is to construct 15 a skein in such a manner as to prevent sand, dirt, or any foreign substance from finding lodgment upon the axle.

A further object of my invention is that by the manner in which I construct my improved skein the hoods and shields now made 20 use of are entirely dispensed with.

Figure 1 is a side elevation of my complete skein with the axle-box in position. Fig. 2 is a vertical longitudinal sectional view of the 25 skein and axle-box in their relative position, showing the construction. Fig. 3 is a top plan view with a part broken away. Fig. 4 is a bottom plan view of the same.

In the construction of the device as shown 30 I provide a body 1, integral with which is formed a cylindrical tapering portion 2, which is the axle of the skein. At the base of the axle, where it terminates into the body 1, is formed a curvilinear flange 3, arranged to 35 project over the axle-box 4 and extend within a short distance from the hub of the wheel, being indicated by the dotted line in Fig. 2. The flange, as will be observed by referring to Fig. 2, is tapered at an angle from a point 40 about the center of the body downward to the bottom and its edge gradually rounded, as indicated by the numeral 5, the purpose of this being to allow all foreign substances or objects which might pass within the recess 45 6, formed by the flange, to pass out. Thus by the shape of the flange such substances cannot remain therein nor find their way upon the axle within the axle-box.

I provide upon the axle-box 4 a curved 50 flange 7, which is constructed to fit within

the recess 6 and is also for the purpose to assist in preventing foreign objects from lodging upon the axle.

The body is provided with suitable flanges, between which are passed suitable clips for 55 supporting the skein upon the axle-bar. I also provide a nut 8 with a flange 9, which projects within the recess of the hub and over the end of the axle-box, which also prevents sand, dirt, or like material from entering. 60

In applying the box within the hub I insert it until the ends 10 of the lugs 11, formed on the box, are flush with the end of the hub, and act as a guide to limit the insertion. 65

The device is simple in construction, its cost is nominal, and has extraordinary advantages over the common skein.

The essential feature of this invention is the manner in which the flange and recess are 70 formed, terminating into a perfect curve, as viewed from the bottom.

Having fully described my invention, what I claim is—

1. A wagon-skein of the class described, 75 comprising a suitable body provided with a recess formed by a flange, said flange tapering at the bottom and having its lower edge rounded, a flanged axle-box constructed to fit within the recess to prevent foreign objects from entering the axle substantially as specified.

2. A device of the class described, comprising a skein provided with a projecting flange, a recess formed all around the skein by said 85 flange, the lower portion of the flange being tapered and its inner edge rounded, an axle-box provided with an upturned flange to correspond with the recess, each when in position preventing sand or dirt from entering between the axle and box, and a flanged nut provided to prevent such substance from entering from the outer end, substantially as 90 specified.

In testimony whereof I affix my signature 95 in presence of two witnesses.

EDWARD H. DEWES.
